UNITED STATES PATENT OFFICE.

LAURENCE E. BLOOD, OF BOSTON, MASSACHUSETTS, ASSIGNOR TO S. A. WOODS MACHINE COMPANY, OF BOSTON, MASSACHUSETTS, A CORPORATION OF MASSACHUSETTS.

WOODWORKING MACHINE.

Application filed December 16, 1926. Serial No. 155,189.

This invention relates to woodworking machines and aims to provide in such a machine a cutter, the operative position of which will be governed by the work on which it acts. The construction may be, and in practice ordinarily would be, embodied in a "profiler" forming a part of a planing or matching machine having cutters to dress the wood, the profiler acting subsequently to 10 the other cutters of the machine.

My invention will be well understood by reference to the accompanying drawings, wherein is disclosed such portion of a woodworking machine of the type referred to as is necessary for an understanding of the present invention, and in these drawings:—

Fig. 1 is an end elevation of the top profiler;

Fig. 2 is a side elevation;

20 Fig. 3 is a section on the line 3—3 of Fig. 1;

Fig. 4 is a plan view with parts omitted and parts broken away;

25 Fig. 5 is a section on the line 5—5 of Fig. 1;

Fig. 6 is a perspective view of the chip-breaker bar and the tensioning mechanism therefor as seen from the intake side, adjacent parts being broken away or omitted;

30 Fig. 7 is a section on the line 7—7 of Fig. 1; and

Fig. 8 is a diagrammatic view to be referred to.

Referring to Fig. 8, I have there represented in a conventional manner a board *b* such as might be delivered from a matching machine with its four sides finished by the usual top, bottom and side cutter heads passing over a supporting table *T*. I have 35 illustrated in a diagrammatic manner a rotary cutter head *c* operating on this board to form grooves therein. This operation is common in the preparation of ceiling and beaded sheathing. The important thing 40 about such grooves is the depth as measured from the upper surface of the board in the position of Fig. 8. In other words, the axis of rotation of the cutter head should be a definite distance from the finished upper 45 surface of the board. If one board is thinner than another and the grooves are to be cut the same depth, the distance of the cutter from the table *T* should correspondingly vary and the distance from the tops

of the boards should remain constant. It is 55 therefore desirable to provide a machine in which the position of the cutter is governed by the upper surface of the work on which it acts. Also, in the operation of such machine, if there is a breakage and one board 60 rides on top of the other, the cutter may be raised and will continue to operate on the upper board, finishing it in proper manner and continuing in this way until the difficulty is removed. 65

I shall now describe the particular embodiment of the invention illustrated in the first seven figures which discloses a profiler top head with an integral electric drive for the cutter and which would ordinarily be 70 organized as a part of a complete matching machine, being located adjacent the feeding out end thereof and being adapted to receive the boards after they have passed through the customary cutters adapted to dress the 75 four sides thereof.

Referring to Fig. 2, on the side frames 9 of the machine there is supported the frame for the profiler mechanism which may be denominated the cutter head stand and 80 which embodies the sides 11 connected by upper and lower cross members 13 and 15, as best shown in Fig. 3. Mounted for bodily vertical movement upon this stand is a cutter head yoke which may take the form (see 85 Fig. 1) of a substantially rectangular frame having vertical side members 17 and 19 connected by upper and lower transverse members 21 and 23 respectively, the work, as will be well understood, passing through the central opening of the frame. The vertical sides 17 and 19 provide for the support of the shaft of the rotating cutter head *c* conventionally illustrated in the figures, and I have herein shown the part 17 as provided 90 with a suitable bracket or shelf 24 on which is mounted a bearing 26 integral with the end plate 25 of the electric motor, the armature shaft of which is continued at 27 to receive the cutter head *c*, the shaft also being 95 supported in a suitable outboard bearing 29 carried by a somewhat similar shelf or bracket on the opposite side 19 of the frame. 100

To support the cutter head yoke on the stand the side members 17 and 19 may be 105 provided (see Fig. 4) with flanges 33 overlying the sides of the upright frame members 11, to which flanges are attached by

bolts 34 the gib plates 35 providing a way or groove receiving the sides of the uprights on which the cutter head yoke slides as on a track. This gib connection provides more particularly for restraining the cutter head yoke from movements which might be considered as partial rotations longitudinally of the machine and as seen in Fig. 4 the gib provided by the sides of the uprights 11 are relatively narrow longitudinally of the machine and widely spaced transversely thereof. To further restrain the yoke, particularly against movement corresponding to rotations transversely of the machine, there may be secured to the cross members 13 and 15 (see Figs. 3 and 4) gib blocks 37 and 39 adapted to be received in suitable ways on the transverse cross members 21 and 23 of the yoke, the connection in the former instance being shown in detail in Fig. 4 as embodying a fixed flange 41 and an adjustable gib 43 secured by screws 45 and backed up by the bolts 47 resting against flange 49, the gib block 39 being similarly guided on the cross member 23 of the yoke. Particularly because of the weight of the driving motor the strains tending to rotate the yoke transversely of the machine are severe. The gibbed connection provided by the blocks 37 and 39 resist such strains at widely spaced points and the blocks are relatively narrow. Similarly the gib provided by the sides of the uprights 11 are (see Fig. 4) narrow longitudinally of the machine but widely spaced transversely thereof. An adequate and efficient guiding is thus provided.

To provide for supporting the cutter head yoke from the work the upper cross member 21 may have (see Fig. 3) a downward extension 51 terminating in a more or less upright depending flange 53 to which may be secured by the bolt and slot connection shown, which provides for vertical adjustment, one of the flanges of the angular chip-breaker bar 55 which may have its edge portions (see Fig. 6) guided in suitable ways at the sides of the flange 53 provided for by suitable rearwardly directed flanges 57 thereon to which are secured the gib plates 59. To the rearwardly directed flange of the chip-breaker bar 55 may be secured by the bolt and slot connection illustrated in Fig. 3, which provides for an adjustment longitudinally of the machine, a series of shoes 61, the ends of which are adapted to rest upon the work and, by means of the adjustments described, may be located in fixed relation to the periphery of the adjacent cutter head *c*. In the normal operation of the parts wherein the cutter head yoke reciprocates the bolts supporting the chip-breaker bar 55 and the shoes 61 are clamped so that there is no movement in the slots and it will be understood that as a board approaches from the right in Fig. 3

it will ride under the shoes 61 and consequently will raise the cutter head yoke bodily so that the cutter *c* carried thereby will be definitely positioned at a desired distance above the top surface of the board, 70 depending upon the initial adjustment given to the parts.

I provide means whereby the effective pressure exerted upon the work by the moving parts may be determinately varied. 75 Thus, in such a machine as is illustrated the weight of the yoke, motor and the like might be in the neighborhood of 1500 pounds and with a structure merely such as has been so far described the shoes 61 would bear with this pressure on the work and the cutter head would be pressed down against the work under this great weight. By means of suitable mechanism, an illustrative example of which I am about to describe, this weight may be in part counterbalanced so that the pressure upon the work may be only such as to give the best results. For instance, it might be desirable to make it equivalent to a weight of about 40 pounds. Referring to Fig. 1, I have herein shown as extending from the lower cross member 23 of the cutter head yoke substantially in line with the center of gravity of the yoke, motor, etc., a screw shaft 63 swivelled in a bracket 65 on the lower cross member and adapted to be turned through the mitre gears 67 by means of a horizontal shaft 69 extending along said cross member and having its end 71 presented at the side of the machine for convenient manipulation, the end 71 being herein shown as squared to receive a removable crank in the nature of a socket wrench. The screw 61 taps into a threaded block or nut 73 which may be provided, as shown in Fig. 7, with suitable dovetailed ribs whereby it is non-rotatably but slidably held in a dovetailed way 75 forming a bracket 77 secured to one of the side frames 9 of the machine. Reverting to Fig. 1, the end of the nut 73 may rest upon a lever 79 secured to a shaft 81 carrying a crank 83 to which is pivoted a rod 85 extending out to one side of the machine and passing adjacent its pivot through a suitable fixed abutment 87. A strong spring 89 surrounds the rod and bears on abutment 87. The tension of this spring may be adjusted by a suitable nut 91, herein shown as taking the form of a hand wheel, threaded on the rod and disposed at one side of the machine for convenient access. As is clear from Fig. 1, the weight of the cutter head yoke and the parts carried thereby, acting through the lever system described, is counterbalanced by the tension of the spring 89 which may be adjusted as desired by means of the nut 91. The spring provides for counterbalancing action without introducing an objectionable factor of inertia. In 130

other words, it readily reacts to movement of the yoke and at the same time has no tendency to move excessively because of momentum. There may also be placed under the end of the arm 79 and in line with the nut 73 a suitable dash pot 93, not necessary to illustrate in detail.

It will be clear that by turning the shaft 69 the nut 73 will be screwed up or down 10 and the leg-like support which the nut and screw provide will be extended or contracted so as to give an initial vertical adjustment to the cutter head yoke system which will have no effect whatever upon the counter-balancing thereof. That is, a vertical adjustment is provided for which will not affect the predetermined pressure with which the profiler mechanism acts upon the work.

Under certain circumstances, it may be desired temporarily fixedly to position the cutter head yoke so that its position will not be governed by the upper surface of the work but will be definitely related to 25 the fixed surface over which the work passes. Under these circumstances the shoes 61 may be utilized as yielding chip-breaker shoes. I shall next describe suitable means whereby the mechanism may be converted in this 30 manner.

For clamping the cutter head yoke in fixed vertical position on the cutter head stand I may provide the mechanism best shown in Figs. 1 and 2 and comprising eye bolts 95 passing through the flanges 33 and gib plates 35 of the cutter head yoke, the eye portions bearing on pressure blocks 97 resting against said plates and receiving at each side of the machine a vertical rod 40 99 having one side flattened off, as shown in Fig. 5, the rod acting in the manner of a cam shaft. When the cutter head floats the rods 99 are turned to present their flat surfaces toward the gib plates 35 and the 45 bolts exert no clamping action. When it is desired to clamp the cutter head yoke against vertical movement, the rods are turned to the position shown in Fig. 5 and the gib plates 35 are forced with a clamping 50 pressure against the side members 17 and 19 with which they cooperate. To facilitate the clamping action the flanges 33 may be cut away as indicated at 100 in Fig. 5 so that the gibs 35 are supported on a relatively narrow land at the outer edge thereof. For operating the rods 99 (see Fig. 1) one may be provided with a handle 101 and may be connected by the parallel cranks 103 and connecting rod 105 to the rod 99 60 at the opposite side of the machine so that the two rods may be operated in unison by means of the single handle 101.

Referring now to Figs. 3 and 6, when the cutter head yoke is so clamped, the bolts securing chip-breaker bar 55 to the flange

53 may be slacked off to permit the chip-breaker bar to reciprocate substantially vertically on the latter, this being permitted by the slot connection shown. To provide a yielding tension on the shoes 61 I may 70 utilize the mechanism best shown in Fig. 6. As there shown, the chip-breaker bar 55 is suspended by the rods 105 pivoted thereto on either side from crank arms 107 secured to and turning with the shaft 109 which may be journaled in brackets 111 and 113 secured, as best shown in Fig. 1, to the upper cross member 11 of the cutter head frame. Suitable set screws 115 provided on these brackets limit the rocking movement of the cranks and shaft in one direction corresponding to downward movement of the chip-breaker. To provide a yielding tension on the chip-breaker the shaft 105 may be provided at one side with an arm 85 117 to which is pivoted a threaded rod 119 passing through a suitable abutment 121 carried by bracket 111 against which rests spring 123 surrounding the rod and adapted to be tensioned by the terminal nuts 125 90 thereon. Upward movement of the chip-breaker bar obviously tends to rotate shaft 109 and arm 117 counterclockwise viewing Fig. 6, tensioning spring 123 between the nuts 125 and abutment 121.

To permit the pressure of the chip-breaker to be quickly released when desired the other end of the shaft 109 may be provided with arm 127 connected by a link 129 to a crank 131 mounted on the short shaft 133 having 100 a supporting journal 135 forming a part of the bracket 113 but omitted for clearness in Fig. 6, which shaft has an operating handle 137 conveniently located at one side of the machine. Turning handle 137 rocks arm 131 and with it arm 127 and the chip-breaker may thus be quickly raised manually.

I have described in detail one particular embodiment of my invention but it will be understood that the construction and arrangement of parts may be widely varied without departing from the spirit of the invention.

What I claim as new and desire to secure 115 by Letters Patent I shall express in the following claims:

1. In a machine of the type described, in combination with the table over which the work is fed, a cutter head yoke freely reciprocable vertically and carrying a cutter head overlying the table, shoes carried by the yoke to ride on the work on the table whereby to position said yoke, a lever system on which the yoke rests and means projecting at 120 the side of the machine for manipulation for applying a variable counterbalancing pressure to said system for counterbalancing a desired portion of the weight of the yoke 125 and parts thereon.

2. In a woodworking machine, in combination with the table over which the work is fed, a cutter head yoke freely reciprocable vertically and carrying a cutter head overlying the table, shoes carried by the yoke to ride on the work on the table whereby to position said yoke and means comprising an adjustably tensioned spring for supporting a desired portion of the weight of the yoke and parts thereon free from any additional factor of inertia.

3. In a woodworking machine, in combination with the table over which the work is fed, a cutter head yoke freely reciprocable vertically and carrying a cutter head overlying the table, shoes carried by the yoke to ride on the work on the table whereby to position said yoke, a lever on which the yoke may rest, a crank turning with the lever, a rod projecting from said crank outwardly beyond the side of the machine, an abutment cooperating with said rod, a spring encircling the rod and resting on the abutment, and a nut threaded on the outer end of the rod for tensioning the spring to apply a variable supporting force to the yoke.

4. In a woodworking machine, in combination with the table over which the work is fed, a cutter head yoke freely reciprocable vertically and carrying a cutter head overlying the table, shoes carried by the yoke to ride on the work on the table whereby to position said yoke, an adjustable counterbalancing means and means for engaging the yoke with said means having provision for adjusting the normal vertical position of the yoke independently of the tension of said counterbalancing means.

5. In a woodworking machine, in combination with the table over which the work is fed, a cutter head yoke freely reciprocable vertically and carrying a cutter head overlying the table, shoes carried by the yoke to ride on the work on the table whereby to position said yoke, an extensible leg depending from the yoke, means comprising an operating handle at the side of the machine for extending and contracting the same and an adjustably yieldable supporting mechanism on which said leg rests.

6. In a woodworking machine, in combination with the table over which the work is fed, a cutter head yoke freely reciprocable vertically and carrying a cutter head overlying the table, shoes carried by the yoke to ride on the work on the table whereby to position said yoke, an extensible leg depending from the yoke, means comprising an operating handle at the side of the machine for extending and contracting the same, a yieldable support on which the leg rests and means comprising an operating portion disposed at the side of the machine for adjusting the resistance of said support.

7. In a woodworking machine, in combination with the table over which the work is fed, a cutter head yoke freely reciprocable vertically and carrying a cutter head overlying the table, shoes carried by the yoke to ride on the work on the table whereby to position said yoke, an extensible leg depending from the yoke, means comprising an operating handle at the side of the machine for extending and contracting the same, a rest beneath the leg, a spring acting on the rest to sustain the yoke, and means comprising an operating portion disposed at the side of the machine for adjustably tensioning the spring.

8. In a woodworking machine, in combination with the table over which the work is fed, a cutter head stand comprising standards lateral of the table, a substantially quadrilateral yoke encircling said table, the upright or side elements of said yoke having sliding engagement with said standards resisting rotative movement of the yoke lengthwise of the machine, a driving motor supported on one of said side elements and carrying a cutter-receiving spindle which extends across the yoke, relatively narrow gibbed connections on the transverse elements of the yoke providing widely spaced guides resisting rotation of the yoke transversely of the machine and shoes carried by the yoke adapted to ride on the work and thereby effect reciprocation of the yoke along the guiding means described.

9. In a woodworking machine, in combination with the table over which the work is fed, a cutter head stand, a yoke carried thereby having shoes for contact with the work for reciprocation of said yoke thereby, a driving motor supported from the yoke in overhung relation to one of the fore and aft faces thereof and carrying a cutter-receiving spindle, said yoke having long vertical flange portions interlocking the stand to resist rotative movements of the yoke longitudinally of the machine and transversely narrow gibs widely spaced at opposite sides of the table and resisting rotative movement of the yoke transversely of the machine.

10. In a woodworking machine, in combination with the table over which the work is fed, a slidable yoke having shoes for contact with the work for reciprocation of said yoke thereby, a bracket on the yoke supporting a driving motor having a cutter-receiving spindle and means to support said yoke on the fixed frame-work of the machine comprising gibs narrow longitudinally of the machine and interlocking the yoke at widely transversely spaced points thereof and other gibs relatively narrow transversely of the machine interlocking the yoke at widely vertically spaced points thereof.

11. In a machine of the class described, in combination with the cutter head stand

having guiding surfaces at the sides, the cutter head yoke having flanges overlying said sides and gib plates extending inwardly over the sides thereof, releasable means 5 for forcing said plates with a clamping pressure against the stand, a portion of said yoke providing supporting ways for a chip-breaker bar, and means for alternatively fixedly or slidably securing the bar in said 10 ways.

12. In a machine of the class described, in combination with the cutter head stand having guiding surfaces at the sides, the cutter head yoke having flanges overlying said 15 sides and gib plates extending inwardly over the sides thereof, said gib plates having a clearance from the stand at the inward portions thereof, clamping means cooperating with said portions and the stand and having 20 a slidable connection with one of said parts to permit vertical movement of the yoke when the clamping means are released, and means for operating said clamping means.

13. In a machine of the class described, in 25 combination with the cutter head stand having guiding surfaces at the sides, the cutter

head yoke having flanges overlying said sides and gib plates extending inwardly over the sides thereof, clamping devices at the sides of the yoke cooperating with the stand 30 for securing the former in fixed position on the latter and having sliding connection with one of said parts to permit vertical movement of the yoke when the clamping devices are released, and means common to said devices on both sides of the machine and having a single actuating handle for simultaneously operating all said devices.

14. In a machine of the class described, in combination, a cutter head stand, a cutter head yoke slidably associated therewith and having means for clamping it in position thereon, spring means for supporting the yoke, a chip-breaker bar slidably carried by the yoke with provision for immovably clamping the same, shoes on the bar for contact with the work, and tensioning means 40 for said bar supported from the yoke.

In testimony whereof, I have signed my name to this specification.

LAURENCE E. BLOOD.
